UNITED STATES PATENT OFFICE.

HARRY W. SHRYOCK, OF EVERSON, WASHINGTON.

ELECTRIC-LIGHTING SYSTEM FOR AUTOMOBILES.

1,199,210.

Specification of Letters Patent. Patented Sept. 26, 1916.

Application filed August 26, 1915. Serial No. 47,893.

To all whom it may concern:

Be it known that I, HARRY W. SHRYOCK, a citizen of the United States, and a resident of Everson, in the county of Whatcom and State of Washington, have invented certain new and useful Improvements in Electric Lighting Systems for Automobiles, of which the following is a specification.

My invention relates to improvements in lighting systems for automobiles; and the object of my invention is to provide convenient means to continue the lighting current through the remaining headlight lamp after one lamp has burned out, when said lamps are connected in series. I accomplish this object with the devices and connections illustrated in the accompanying sheet of drawings in which—

Figure 1 is a plan view of a switch designed for my new system and the upper portion of the steering-wheel column of an automobile to which it is attached, Fig. 2 is an elevation view in vertical section on the line $y-y$ of Fig. 1; Fig. 3 is a diagram 25 of the apparatus and electrical connections comprising my system required for installing in an automobile. Fig. 4 is an end elevation of my switch detached from said column and Fig. 5 is a plan view of the same 30 from the bottom.

Similar characters refer to similar parts in the several views.

Certain parts are broken into in order to show parts hidden thereby.

More particularly: The upper part of the front of the column of an automobile steering wheel is shown at 1. The insulating base 2 of an electric switch is fitted to said column. Fastening bands 2^a, 2^a attached to base 2 with screws clamp said base to said column. Concentric segments 2^b, 2^c, 2^d, 2^e, and 2^f are embedded in base 2 flush with the upper surface of the same. A disk 2^g having a central tapped hole is attached to the center of base 2 concentric with said segments. A cover 3 is retained over segments 2^c—2^f by screw stud 3^e engaged in the threaded hole in disk 2^g. Said screw stud has a shoulder seated on said disk and 40 mounts cover 3 on said stud for rotation over said segments. Diametrically opposed knobs 3^a, 3^a are rigidly attached to cover 3 and furnish finger holds when revolving said cover. A brush bar 4 is fitted into

the upper part of cover 3 diametrically 55 across the same. Bar 4 has end slots 4^a, 4^c which engage with ribs 3^b, 3^b on the sides of said cover and cause bar 4 to rotate with cover 3. A central hole through bar 4 permits said bar to be mounted for rotation 60 on stud 3^c. A nut on said screw stud retains said cover in place. Two spring brushes 4^a and 4^b are attached to the lower side and near the ends of bar 4 in such manner that each of said brushes may slide on 65 and electrically connect any two of the juxtaposed concentric segments 2^c, 2^d etc. when cover 3 is rotated. Said springs are so shaped that they may lie between the juxtaposed ends of said segments without contact with the same as shown in Fig. 4. Each of said segments is connected to an insulated wire 5 as shown in Fig. 5. Said wires 5, 5 etc. are embedded in grooves in the bottom of base 2 and pass downward 75 from said base along column 1 as shown in Figs. 1, 2, 4 and 5.

In the diagram Fig. 3 the switch segments 2^c—2^f are arranged as in Figs. 1 and 2, and these together with the right-hand lamp 9, the left-hand lamp 10, the constantly driven magneto 8, the resistance coil 7 and the connecting wires 5, 5, etc., comprise all of my lighting system except the movable parts of the switch. The brush 85 bar 4 of this switch is shown in dotted outline in Fig. 3 in four operative positions at 4, 4', 4'' and 4'''. Dotted lines 4^d, 4^d; 4^e, 4^e; 4^f, 4^f and 4^a, 4^a in Fig. 3 show the lines of contact and connection between 90 the brushes 4^a and 4^b and the segments 2^b, 2^c, 2^d, 2^e and 2^f when bar 4 occupies its four operable positions in rotation. One terminal of each of lamps 9 and 10 are connected together by wire 6 and to one terminal of 95 resistance coil 7 by wire 6^a. The other terminal of said coil 7 is connected to segment 2^f. One terminal 8^b of magneto 8 is connected to the frame of the same as usual, said magneto frame is connected to segment 100 2^b, and its brush 8^a is connected to segment 2^c. The other terminal of lamp 9 is connected to segment 2^c, while the other terminal of lamp 10 is connected to segment 2^d.

The operation of the switch to control the 105 current supply of the lamps is easily understood from Fig. 3 when it is noted that each of the brushes 4^a and 4^b, Fig. 2, always

forms an electrical connection between the concentric, juxtaposed, switch segments on which it lies, and when said brush rests on the insulation between the juxtaposed ends 5 of said segments the electric circuit is broken. Thus when the brush bar is in position 4", Fig. 2, no current can pass the switch, hence the lamp circuit is open. When said brush bar is in position 4''' the 10 current from magneto 8 passes through lamps 9 and 10 in series. When brush bar 4 is in position 4 said current passes through lamp 9 and resistance coil 7 in series, lamp 10 being cut out. And when said bar is in 15 position 4' said magneto current passes through lamp 10 and coil 7 in series, lamp 9 being cut out. Therefore by setting cover 3 in the proper position in rotation the circuit through lamps 9 and 10 can be opened, 20 established through both lamps in series, or either lamp alone at will, thus providing for the use of one of the headlights when the other is not usable.

Having thus described my invention, what

I claim as new and desire to secure by Letters Patent is,

The combination of a magneto; a resistance coil; two electric lamps; and the base of an electric switch having concentric inner and outer rings of segments, the two 30 segments of said inner ring connected to the terminals of said magneto, one of the three segments of said outer ring connected to one of the terminals of said resistance coil and each of the other two outer segments connected to one of the terminals of said lamps, and the other terminals of said lamps connected together and to the other terminal of said resistance coil; with two diametrically opposed brushes slideable on said concentric 35 segments.

Signed at Bellingham in the county of Whatcom and State of Washington this 20th day of August A. D. 1915.

HARRY W. SHRYOCK.
